TRANSPORTING MEANS FOR CAN
WASHERS

John M. McClatchie, New York, N. Y., assignor to
The Borden Company, New York, N. Y., a corporation of New Jersey

Original application May 7, 1931, Serial No.
553,673. Divided and this application February
20, 1933, Serial No. 657,545

6 Claims. (Cl. 198—218)

This invention relates to an improvement in machines for washing cans and the like. This application is a division of my co-pending application, Serial No. 535,673, filed May 7, 1931.

5 The object of the present invention is to simplify and improve the construction and mode of operation of certain of the parts of the machine disclosed in said application and particularly the can-conveying means, as hereinafter fully described and particularly pointed out in the appended claims.

In the machine of this present invention, the cans to be washed are moved by a carriage from a position over one cleansing nozzle to a position 15 over the next until the cans have each been subjected to a series of cleansing operations. The carriage or conveyor by which the cans are carried from one nozzle to the other, is moved with an upward, forward, downward and backward 20 movement and when a cleaned and dried can carried thereby reaches the exit end of the machine, it is uprighted on the upstroke of the carriage. In this structure also, covers for the cans are advanced through the machine pari passu with 25 the cans, and means are employed for placing the covers within range of the cover advancing means. The machine of the present invention is provided with novel means for preventing the cans from toppling over during their advance from nozzle 30 to nozzle.

In the accompanying drawings, Fig. 1 is a sectional elevation of the discharge end of the machine, the section being taken on the line 1—1 of Fig. 3, looking in the direction of the arrows; 35 Figs. 2 and 3 taken together are a longitudinal section through the machine with the valves for controlling the supply of cleansing fluid to the nozzles, and most of the valve-operating mechanism, omitted; Fig. 4 is a side elevation, with 40 parts in section, of the discharge end of the machine; Fig. 5 is a transverse section through the can carriage and associated parts; and Fig. 6 is an elevation, partly in section, of the left hand side of the machine.

45 The improved can washing machine as illustrated in the drawings is provided with two longitudinally extending bars 29 on which the cans 30 are supported in inverted position during the various cleansing operations for the cans. The 50 bars 29 are provided at intervals throughout their length with legs 31 which rest on cross pieces 32 supported at their outer ends from the upright standards 33 forming part of the main or stationary frame of the machine. The bars 29 extend 55 throughout the length of the machine, one

end of the bars, the right hand end, viewing Fig. 6, being located at the intake end of the machine and the other end of the bars being located at the discharge end of the machine. The nozzles for directing the washing, sterilizing and drying fluids into the cans extend upwardly from the can supporting bars 29 and are arranged at equally spaced intervals, being fixed in position between the bars by means of brackets 35. Each bracket 35 is provided with two oppositely disposed, longitudinally extending wings 36, the upper edges of which are flush with the upper edges of the bars 29. The bracket wings 36 cooperate with the bars 29 in supporting the inverted cans over the nozzles. In this connection it will be observed that although the bars 29 are shown as of unbroken continuity throughout their length, they may consist of a series of interrupted supports like the bracket wings 36, since the cans are not advanced or slid along the bars but are advanced through the machine out of contact with the bars and only rest on the bars during the washing operations, as will be presently explained.

The means for advancing the cans through the machine and depositing them successively over the nozzles comprises two longitudinally-extending, oppositely-faced angle bars 37 which are spaced apart far enough to support on their horizontal webs the flanged mouths of the usual types of large milk cans. The bars 37 rest on the inner 85 ends of the pairs of transversely arranged pieces 38 secured to the lower ends of the outer row of uprights 39 and the inner row of uprights 40. The uprights 39 and 40 are held in spaced relationship by longitudinally extending angle irons 90 42, 43 and 44 secured to their lower ends, and by the channel iron 45 resting on the upper ends of the inner uprights 40, and are braced transversely by the cross pieces 46 and the obliquely arranged braces 47. There is thus produced a 95 light movable frame or carriage rigid enough to lift all the cans in the machine simultaneously and transport them through the machine by a step by step movement. To the inner surfaces of the outer row of uprights 39 is secured a guard 100 plate 48 and to the inner surfaces of the inner row of uprights 40 is secured a guard plate 49. The cans are prevented from striking the guard plates 48 and 49 by the longitudinally-extending rails 51 and 52.

The cans are placed manually in the machine at the intake end thereof and they are then advanced through the machine by the carriage to which a four-step cycle of movements is imparted. The first step of the carriage is upward, 110

lifting the cans to a point at which their flanged mouths are above the plane passing through the upper ends of the nozzles. The carriage then moves forward one step toward the discharge end 5 of the machine and at the end of the forward step the carriage descends to lower the cans onto the bars 29, after which the carriage, freed from the cans, returns toward the intake end of the machine into position to pick up the next can 10 which has been placed in the machine.

The means for imparting the four-step cycle of movements to the can transporting carriage comprises two rectangularly shaped gear frames 56 and 57 supported from the lower sides of the 15 angle irons 43 and 44. The gear frames 56 and 57 have parallel sides and are guided in their movements between the longitudinally arranged bars 58 supported on the cross pieces 32. The upper ends of the inner row of up- 20 rights 40 of the can carriage are guided between two longitudinally extending angle irons 53 resting on the transversely arranged channel irons 54 supported on the upper ends of the up- 25 rights 33 of the stationary frame of the machine.

Each gear frame 56 and 57 is provided with a four-sided internal gear, with round corners, 30 adapted to be engaged by a pinion 60. The two pinions 60 are mounted on the inner ends of the transversely arranged shafts 61 journaled at 35 their ends in frames 62 which are supported at their inner ends on the bars 58 and at their outer ends on the angle irons 63 supported from the uprights 33. On the outer ends of the shafts 61 are mounted bevel gears 64 which are driven by pinions 65 mounted on the opposite ends of the longitudinally arranged shaft 66 journaled in brackets 67 projecting outwardly from the frames 62. The shaft 66 may be driven from a 40 conveniently placed motor and for this purpose is provided with a sprocket wheel 68 and chain 69. The shaft 66 rotates in a counter-clockwise direction, viewing Fig. 2. From this it will be understood that while the rotating pinions 60 are in mesh with the teeth of the upper horizontal gear sections 71 the can carriage is traveling 45 backwardly or toward the intake end of the machine, at the right of Fig. 6, that while the pinions are in engagement with the vertical gear sections 72 the carriage is rising or traveling 50 upwardly; that while the pinions are in engagement with the lower horizontal gear sections 73 the carriage is advancing toward the discharge end of the machine, and that while the pinions are in engagement with the vertical gear 55 sections 74 the carriage is descending or traveling downwardly. Since the pinions 60 rotate constantly and the gear sections constitute two internal, rectangular gears, the travel of the can carriage is substantially continuous, even at the 60 points where it changes its direction of travel. However, the end of the backward movement or travel of the carriage toward the intake end of the machine may be regarded as the point of beginning of the four-step cycle of movements 65 of the carriage in transporting the cans through the machine. The cans rest in inverted position on the bars 29 during the whole of the backward stroke of the carriage and are supported by the carriage during the upward, forward and downward strokes of the carriage, it being understood 70 that the carriage deposits the cans on the bars 29 just previous to the completion of the downward stroke, and re-engages the cans just after the beginning of the upward stroke. The can carriage is supported during its upward and

downward movements and also while the pinions 60 are in engagement with the lower gear sections 73 by means of the rolls 76 concentrically aligned with the shafts 61, respectively, and traveling in grooves 77 formed in the rear sides of the gear frames 56 and 57, as shown in Figs. 5 and 6. The rolls 76 are mounted in journals 78 resting on the angle irons 58.

To prevent the cans from toppling over during the forward movement of the carriage, I provide a series of guard arms 80 each consisting of a V-shaped piece of metal the ends of the arms of which are fastened to the longitudinally extending rod 81 journaled in blocks 82 secured to the inner surfaces of the guard plate 49 at the points where the latter are in engagement with the uprights 40. The angle iron 52 overhangs the blocks 82 and rod 81. At the discharge end of the machine the rod 81 is provided with an arm 83 having an offset free end in which is formed a cam slot 84 (see Fig. 1) which receives a fixed rod 85 supported at one end by a bracket arm 86 secured to a drip tank 87 and at its other end by a bracket 88 rising from a rail 89 (Fig. 4) formed on one edge of the discharge platform 90. The disposition of the rod 85 and the cam slot in the arm 83 is such that when the can carriage is on its rearward stroke returning toward the intake end of the machine, the arm 83 is held raised by the rod 85 and the guard arms 80 are thereby held pointed downwardly so as not to interfere with the cans, as shown in Figs. 4, 5 and 6. When, however, the can carriage rises to carry the cans one step toward the discharge end of the machine, the arm 83 is turned by the rod 85 to raise the guard arms 80 into horizontal position between the cans as shown in Figs. 2 and 3, so that if a can should tend to topple over during the forward movement of the carriage it will be caught and held by the adjacent guard arm and returned to normal position on the downward stroke of the carriage depositing the cans on the supports 29. It will thus be understood that the guard arms 80 are moved upwardly between the cans as the carriage rises, continues in horizontal position during the forward step of the carriage and return into inoperative vertical position on the downward travel of the carriage.

The can carriage successively deposits the cans for the successive washing, sterilizing and drying treatments at stations indicated in Figs. 2 and 3 at A, B, C, D, E, F, G, H and I. At each station there is located a nozzle, the nozzles at stations A and B being false nozzles to afford the operator opportunity to place an inverted can in the machine, as at station A, and also to permit the milk or other substance remaining in the can to run out before the can is subjected to the preliminary cold water rinse which occurs at station C, and is followed by a hot water rinse at station D. A washing solution is directed against the inner surfaces of a can at station E and at station F any solution adhering to the can is removed by a hot water rinse. At stations G and H the interior surfaces of the cans are subjected to a steam bath, and at station I a blast of air is directed into the can to dry it.

When the machine is first started in operation the operator places a can in inverted position over the false nozzle at station A. All of the nozzles, including the false nozzles at stations A and B, are provided with radially extending wings 92 over which the mouths of the cans pass and which thereby serve to guide or

- center the cans with respect to the nozzles. At the end of the stroke or travel of the carriage toward the intake end of the machine the rear ends of the angle irons 37 of the carriage are positioned under the can resting on the rear ends of the bars 29 at station A, so that on the upstroke of the carriage the can is lifted from over the false nozzle at station A and on the next forward stroke of the carriage is brought to position over the false nozzle at station B, over which the carriage deposits the can on the down stroke of the carriage and at which it leaves the can as it returns toward the intake end of the machine. While the carriage is depositing the can at station B and until the carriage completes its return movement the operator has opportunity to place another can in inverted position on the bars 29 at station A. On the next upward stroke of the carriage the two cans are lifted simultaneously from the bars 29, and are transported to the next successive nozzles on the next forward step of the carriage, the can at station B being moved to station C and the can at station A being moved to station B. As the carriage continues to pass through its four step cycle of movements, the operator continues to place cans in inverted position over the false nozzle at station A, the cans are successively placed over the succeeding nozzles until there is a can at each station, nine in all. After a can has been placed over the air nozzle at station I to receive the blast of air against its interior surfaces during the backward stroke of the carriage, the dried can is lifted from over the air nozzle on the next upward stroke of the carriage and is then pushed upwardly over a stationary abutment 91 so as to land top side up on a discharge platform 90, the uprighting of the can occurring during the upward and forward strokes of the carriage. During the next downward stroke of the carriage which deposits the next succeeding can over the air nozzle, and the return of the carriage toward the intake end of the machine, the operator has opportunity to place another can over the false nozzle at station A. It is thus seen that nine cans are constantly in the machine during the normal, continuous operation thereof, and that of these nine, seven are simultaneously subjected to cleansing, sterilizing and drying operations, and that as each can is uprigted onto the discharge platform 90, an unwashed can is placed in the machine. It will be understood that in the practical operation of the machine the operator can only place a can in the machine when the can has been emptied, and that consequently many gaps will occur in the line of cans passing through the machine. The valves corresponding to the absent cans will not be operated, but the valves opposite the stations occupied by cans will be operated. The operation of the machine is continuous, the cans being placed in the machine manually and then treated and discharged entirely automatically.
- The nozzles at the various stations, which direct the cleansing and sterilizing fluids against the interior surfaces of the cans, are supplied by a system of piping not shown herein. The pipe leading to each nozzle is provided with a valve so operated that the valve opens only when a can is positioned over the nozzle to which the valve connects. The valve controlling devices are carried by the carriage and are shown at 97, the operation of these devices upon the valves being controlled initially by a device indicated at 101 located adjacent the station B, and which is set in operative position only when a can is located over the nozzle B. Therefore, if no can is picked up at the first station to be carried successively to the next stations, the control members for the valves at the next successive stations will not be set in operative positions and the valves at said stations will not be operated. On the other hand, when a can has been picked up at the first station, the devices for controlling the valves will operate to set the valves so that they will be opened when required. This valve operating mechanism is fully described and claimed in my copending application, Serial No. 535,673, of which this application is a division, so a specific and detailed description of it herein is deemed unnecessary.
- While the cans are passing through the machine and undergoing the washing, sterilizing and drying operations, the covers or tops for the cans are advanced along a runway and subjected to similar cleansing treatments. The covers 220 are supported topside up and are slid along in oblique position on two rails 221 and 222 fixed on the upper edges of the inturned fingers 223 of a series of frames or brackets 224 secured to the cross pieces 54. The rails 221 and 222 extend from a point opposite the false nozzle at station A to a point over the discharge platform, as shown in Figs. 4 and 6.
- The covers are advanced step by step along the rails 221 and 222 by fingers 227 secured to a longitudinally extending bar 228 provided at each end with a boss 229 secured to a shaft 230 journaled in the bearings 231 supported from the cross pieces or braces 232 in the upper part of the frames 224. The shaft 230 lifts the fingers 227 above the plane passing through the top surfaces of the can covers, and is yieldingly oscillated in the opposite direction to place the fingers 227 in cover-engaging position. For this purpose the shaft 230 is provided with an arm 233 having its free end projecting through a slotted plate 234 secured to the upright 40 of the can carriage. A spring 235, attached to the arm 233 and to a pin 236 normally holds the free end of the arm 233 against the top 237 of the slotted plate 234. On the down stroke of the can carriage, the part 237 engages with the arm 233 to depress it and so oscillate the shaft 230 to lift the fingers 227 above the can covers to the position shown in Fig. 4. As the can carriage rises the spring 235 draws the free end of the arm 233 upward and thereby causes the shaft 230 to place the fingers 227 in cover-engaging position, as shown in Fig. 1. If during the movement of the fingers 227 into cover-engaging position, one of the fingers should encounter a misplaced cover, the spring 235 will yield and thus no injury will occur to any of the parts of the machine. While the fingers 227 are held above the tops of the can covers by the engagement of the part 237 with the arm 233, the can carriage is moving toward the intake end of the machine, and while the fingers 227 are in cover-engaging position the can carriage is moving toward the discharge end of the machine and consequently the fingers 227 advance the covers one step. Bar 228 reciprocates in unison with the can carriage because arm 233, which is secured to shaft 230, is always engaged in the slot of member 234 mounted on the carriage.
- Before the operator places a can in inverted position over the false nozzle at station A, he places the cover on a hopper-like chute indicated generally at 240. The chute 240, as best shown

in Figs. 1 and 6, is obliquely arranged and comprises two side or guide bars 241, 242, the lower ends of which are connected, respectively, with the rails 221 and 222, the outer or upper ends 5 of the bars being connected by the cross piece 243. The bars 241 and 242 are supported in position by the bracket 244 extending from the first upright 33 at the right hand side of the machine. The chute is provided with the obliquely arranged 10 bottom 245. When the can is placed in inverted position at station A the cover for the can is placed topside up in the chute, the lower edges of the cylindrical neck of the cover resting on the bottom 245 of the chute. The cover slides down 15 the chute until the cylindrical neck portion thereof rests against the outer end of the lower rail 222, as shown in Fig. 1. Arranged over the lower end of the chute is a directing guard member 246 supported from the first brace 232.

20 Each cover is advanced its first step along the rails 221, 222, by means of a pusher lever 248, pivotally mounted on the carriage. Lever 248 has a hub 249 (Fig. 2) rotatably mounted on a shaft 250 supported in brackets 251 secured to 25 the carriage. This hub carries an arm 252 having a can-engaging end 253 so placed that when the carriage rises to pick up a can from over the false nozzle at station A, the arm 252 will be depressed and the pusher lever will be rocked 30 upwardly, so that when the carriage is fully raised the pusher end 254 of lever 248 will come into line with the neck of the can cover. Then, as the carriage makes its forward stroke the cover will be pushed along one step by the pusher. 35 However, if there is no can at station A to be picked up by the carriage as it rises, arm 252 will not become depressed and the pusher lever 248 will not engage the can cover when the carriage advances, but will pass by beneath it. 40 When a cover has been advanced such initial step it is in position to be engaged by the first of the cover-advancing fingers 227.

When a cover is at the base of the chute 240 its position in the machine corresponds with the 45 position of a can placed over the false nozzle at station A. When the machine advances the can from station A to the false nozzle at station B, the cover simultaneously is advanced by means of the pusher lever 248 to a position in the machine corresponding to the position of the can at 50 station B. Now when the carriage, after its return stroke, rises to lift this can from station B preparatory to advancing it to station C, the rising of the control member 234 for the arm 233, 55 which controls the positioning of the cover fingers 227, causes the first cover finger 227 to be lowered into position behind this cover, so that when the raised carriage advances the can to position over station C, the first cover finger 227 60 simultaneously advances the cover along the rails 221 and 222 into a position in the machine corresponding to the position of the can deposited at station C. A cover-washing nozzle is appropriately placed at each station so that a cover advanced to a position above each station will be 65 acted upon by its nozzle.

Thus, each cover is advanced step by step along the rails 221, 222, and from one nozzle to the next in correspondence with the advancement of a can through the machine; that is, a can and a cover start through the machine together and are advanced correspondingly step by step until discharged.

When the cover reaches the seventh cover 70 treating station it receives a blast of air from a

cover treating nozzle 265, which is supplied through a pipe 266 connected to a pipe 151 leading from a conveniently placed air blower. The treatment of both can and cover having now been completed, the can becomes disposed in upright 80 position on the discharge platform 90 and simultaneously the cover is advanced into position for placement on the uprighted can.

As the can is being treated by the air blast at station I, the can carriage completes its return stroke toward the intake end of the machine. The forward ends of the rails 37 of the can carriage are so arranged that on the completion of the return stroke of the can carriage, they will cause the can to be tilted against or onto the abutment 91, and then as the carriage completes its upward movement and moves forward, the can is pushed over the abutment and lands bottom side down on the discharge platform. If a can is not properly uprighted after sliding over the abutment, the uprighting of the can on the discharge platform is completed by means of a pusher arm 270 secured to a shaft 271 journaled in bearings such as 272 secured to appropriate frame members of the machine. Shaft 271 has 100 also secured thereto an operating lever 273 against which a suitable stud or pin 274 carried on the can carriage is adapted to engage as the carriage completes its forward stroke. By this engagement, the operating lever 273 is moved to 105 swing the arm 270 against the rear side of the can and to push the can into upright position in case the can should be leaning against the abutment 91.

The platform 90 extends transversely across 110 the discharge end of the machine and is supported on longitudinal channel irons 280 extending from the last pair of uprights 33 to the final short pair of uprights 281. At its forward edge, the platform 90 is supported by the channel 115 iron 282 extending transversely of the two uprights 281. These uprights are also connected toward their lower ends by an angle iron 283.

The cans are discharged onto the platform 90 at a point in alignment with the bars 29, and here 120 the forward edge of platform 90 is provided with an upright plate 284 which assists in guiding the can into upright position and prevents the uprighting can from toppling off the end of the machine. There is also a guard plate 285 secured along the adjacent side edge of the platform. 125

The uprighted can is now moved transversely across the discharge end of the machine on the platform and receives a spray of water against 130 its bottom from a nozzle 121, and also receives its cover. The uprighted can is moved by an arm 290, having a can-engaging piece 291 at its upper end, is fixed on a shaft 292 journaled in bearings 293. The arm 290 is oscillated by means of 135 a link 295 connected at one end to an arm 296 secured to shaft 292 and connected at its other end with an arm 297 secured to an oscillating shaft 165. Whenever shaft 165 turns in clockwise direction, viewing Fig. 2, the arm 290 will 140 be swung across the platform 90 and will be returned to initial position when the shaft 165 rotates counter-clockwise. The rear edge of platform 90 is cut away, as shown in Fig. 3, to allow 145 for the swinging of arm 290. The pipe 120, which feeds nozzle 121, has a valve 302 having a stem 306 over which is located an actuating member 307 adjustably secured to the under side of a plate 304 hinged at 305 to the platform. This plate 150

304 is normally retained slightly raised above the platform by the pressure of the valve stem 306 against the member 307. When a can is moved across the platform by the arm 290 into position over the plate 304, the weight of the can will depress this plate and consequently depress the valve stem 306, causing the valve to open and a spray of water to issue from the nozzle 121 and impinge against the bottom of the can. The nozzle 121 forms part of the platform 90.

On the next forward stroke of the carriage, the can is pushed forwardly off of platform 90 by an arm 309 on one of the rails 44 of the carriage, and onto the rollers 308 which carry the can away from the machine. Arm 309 has a can engaging end 310 which, when the carriage is raised, comes into line with the can to be discharged. The platform 90 is suitably cut away at 311 to allow for movement of the arm 309 and its can engaging end 310 relatively to the platform, both vertically and horizontally.

On the forward stroke of the carriage which uprights a can onto the platform 90 opposite the discharge end of the bars 29, the cover which has just been subjected to a blast of air over nozzle 265 is advanced to the end of the rails 221 and 222 in position to be pushed off on the next forward stroke of the carriage. Before this occurs, the can is moved across the platform and into position under the ends of the rails 221 and 222, so that on the next or discharging stroke of the carriage—during which the cover is pushed off the rails 221 and 222—the cover will fall onto the open top of the can as the latter is discharged from the machine. Plates 286 are secured to the ends of the rails 221 and 222 to act as a guard for the reciprocating bar 228.

The left hand side of the machine is provided throughout its length and height with a sheathing indicated at 312 and the entire top of the machine is provided with a hood 313.

In the operation of the machine, an operator stands at the intake end of the machine. When he removes a cover from a can, he places the top side up in the chute 240. He then empties the can and places it in inverted position over the false nozzle at station A. The machine now advances this cover and can pari passu through the machine in successive stages or steps from one nozzle to the next until on being raised from the last nozzle the can is pushed into upright position on the discharge platform, after which the can is moved across the discharge platform, its bottom is washed and then as it is discharged from the machine its cover is applied. As soon as the machine has advanced a can from the station A and its cover from the corresponding cover position, the operator may, and is intended to, place another cover in the chute 240 and another can over false nozzle A. The time allotted the attendant to place a cover and a can in the machine is the time consumed by the can carriage subsequent to the removal of a can from station A until it has returned to pick up another can from this station. The attendant, therefore, has no difficulty in placing a cover and can in the machine which may operate at a speed consistent with the utmost speed with which the attendant can properly empty and handle the cans.

In the event that the attendant places a cover in the machine but does not place a can in the machine, the cover will not be advanced on the forward stroke of the carriage because the initial advancement of the cover depends upon the arm 252 being depressed by the flanged mouth of a can

positioned at station A. However, a can may be advanced through the machine without an accompanying cover, but this can be avoided by always placing the cover in the chute 240 before the can is placed on the bars 29 at station A. When the machine is kept loaded to its full capacity, there is a can at each station, and a can is discharged from the machine and a new can is fed into the machine for each cycle of the can carriage movement.

What I claim is:—

1. In a machine of the character described, a can carriage having an upward, forward, downward and backward movement, said carriage being adapted to support and carry cans in predetermined spaced relation thereon during a predetermined part of each cycle of movement, and being adapted to be free of cans during the remaining portion of each cycle of movement, and means on said carriage for preventing displacement of the cans while supported on the carriage, said means including a series of guard arms movable into position between cans supported on the carriage and movable from between the cans when the carriage is free of cans.

2. In a machine of the character described, a carriage having an upward, forward, downward and backward movement, said carriage being adapted to support and carry cans in predetermined spaced relation thereon during a predetermined part of each cycle of movement and being adapted to be free of cans during the remaining portion of each cycle of movement, means on the carriage for preventing displacement of the cans while supported on the carriage, said means including a shaft provided with guard arms, and means for rocking said shaft to place and retain said guard arms between cans supported by the carriage when said cans are so supported, and for rocking said shaft to remove said guard arms from between said cans when the carriage is free of the cans.

3. In a machine of the character described, a can carriage having horizontal and upward and downward vertical movement, said carriage being adapted to support and carry cans in predetermined spaced relation thereon during a predetermined part of each cycle of movement and being adapted to be free of cans during the remaining portion of each cycle of movement, and means on the carriage for preventing displacement of the cans while supported on the carriage and while the carriage is moving upwardly and horizontally forward, said means including guard arms projecting between the cans supported on the carriage and movable from between the cans on the downward travel of the carriage.

4. In a machine of the character described, a can carriage having an upward, forward, downward and backward movement, said carriage being adapted to support and carry cans in predetermined spaced relation thereon during a predetermined part of each cycle of movement, and being adapted to be free of cans during the remaining portion of each cycle of movement, a series of guard arms supported on and moved with the carriage, said guard arms being so positioned relative to the spaced cans on the carriage that said arms are movable into the spaces between the cans while the cans are supported on and are being carried by the carriage and means for moving the arms in unison with an oscillatory movement to remove them from between the cans when the cans are freed from the carriage.

5. In a machine of the character described, a carriage having an upward, forward, downward and backward movement, said carriage being adapted to support and carry cans in predetermined spaced relation thereon during a predetermined part of each cycle of movement, and being adapted to be free of cans during the remaining portion of each cycle of movement, and means on said carriage for preventing displacement of the cans while supported on the carriage during the upward and forward movement of said carriage, said means including guards movable into position between cans supported on the carriage and maintained in such position while the carriage is moving upwardly and forwardly, and movable from between the cans when the carriage is free of cans.

6. In a machine of the character described, a

carriage having an upward, forward, downward and backward movement, said carriage being adapted to support and carry cans in predetermined spaced relation thereon during a predetermined part of each cycle of movement and being adapted to be free of cans during the remaining portion of each cycle of movement, and means on the carriage for preventing displacement of the cans while supported on the carriage, said means including a rock shaft supported on the carriage and provided with spaced V-shaped guard arms projecting laterally from it, and means for rocking said shaft to project the guard arms horizontally between the cans when the cans are supported on the carriage, or to remove said guard arms from between the cans when the carriage is free of the cans.
